US0D1027639S

(12) **United States Design Patent** (10) **Patent No.:** **US D1,027,639 S**
(45) **Date of Patent:** **** May 21, 2024**

(54) **LID**

(71) Applicant: **SWIMC LLC**, Cleveland, OH (US)

(72) Inventors: **Richard D. Hudson**, North Olmstead, OH (US); **James J. Johnson**, Akron, OH (US); **Gustavo A. Morales**, Brunswick, OH (US); **Edward Ray Goodwin, Jr.**, Westlake, OH (US); **Michael C. Lambertson, Jr.**, Aurora, OH (US); **Charles T. Buckel, Jr.**, Valley City, OH (US)

(73) Assignee: **SWIMC LLC**, Cleveland, OH (US)

(**) Term: **15 Years**

(21) Appl. No.: **29/894,570**

(22) Filed: **Jun. 12, 2023**

Related U.S. Application Data

(63) Continuation of application No. 29/771,293, filed on Feb. 22, 2021, now Pat. No. Des. 993,021, which is a continuation of application No. 29/728,716, filed on Mar. 20, 2020, now Pat. No. Des. 914,506, which is a continuation of application No. 29/676,804, filed on Jan. 15, 2019, now Pat. No. Des. 885,185, which is a continuation of application No. 29/645,163, filed on Apr. 24, 2018, now Pat. No. Des. 843,837, which is a continuation of application No. 29/559,219, filed on Mar. 25, 2016, now Pat. No. Des. 824,766.

CLAIM

The ornamental design for a lid, as shown and described.

DESCRIPTION

FIG. 1 is a perspective view of a lid showing our new design; FIG. 2 is a top view of the lid in FIG. 1; FIG. 3 is a bottom view of the lid in FIG. 1; FIG. 4 is a left side view of the lid in FIG. 1 with the right view being a mirror image thereof; FIG. 5 is a front view of the lid in FIG. 1; and, FIG. 6 is a rear view of the lid in FIG. 1. The broken lines show portions of the design that form no part of the claimed design. The dot-dash lines represent boundaries of the claim and form no part thereof.

1 Claim, 3 Drawing Sheets
